United States Patent Office

Des. 203,288
Patented Dec. 21, 1965

203,288

TRAY

Alfred D. Duncan, Elmhurst, Ill., assignor to Duncanlite Laboratory, Inc., Villa Park, Ill., a corporation of Illinois

Filed Feb. 3, 1965, Ser. No. 83,676

Term of patent 14 years

(Cl. D44—10)

FIG.1

FIG.2

FIG. 1 is a front perspective view of the tray embodying the new design; and

FIG. 2 is a rear perspective view of the tray shown in FIG. 1.

The bottom of the tray is substantially plain and unornamented.

I claim:

The ornamental design for a tray, as shown and described.
